Inventor

Robert S. Dunning

United States Patent Office.

ROBERT S. DUNNING, OF FALL RIVER, MASSACHUSETTS.

Letters Patent No. 89,641, dated May 4, 1869.

IMPROVED KEY-FASTENER.

The Schedule referred to in these Letters Patent and making part of the same.

To all whom it may concern:

Be it known that I, ROBERT S. DUNNING, of Fall River, in the county of Bristol, and State of Massachusetts, have invented a new and improved Key-Fastener, for preventing burglars from entering lodging-rooms, by turning or removing keys when left in the locks; and I do hereby declare that the following is a full and exact description thereof, reference being had to the accompanying drawings, and to the letters of reference marked thereon.

My invention consists in a metallic bar, perforated with holes, a bolt, and a pin. The bar is affixed in the lock, under the key; the bolt passed through the bow of the key, and also through the bar. The head of the bolt rests on the bow of the key. The pin secures the bolt in the bar.

Figure 1 is a perspective view of a door with my invention applied to the lock.

Figures 2 and 3 are sectional views of the bar.

Figure 4 is a perspective view of the bolt.

Fig. 1. A¹ is the door.

B¹ is the key in the lock.

C¹ is the "bar," affixed in the lock, under the key.

D¹ is the bolt, passing through the bow of the key, and also through the "bar."

E¹ is a pin, passing through the bolt, under the bar.

Fig. 2. A² is the portion of the bar which enters the lock.

B², the part which projects, showing the holes through which the lower part of the bolt passes.

Fig. 3 is a profile view of the bar.

A³ is the part which enters the lock.

B³, the part which projects.

The bar is curved, to accommodate it to keys which do not have bows, but disks. When such keys are used, the bolt is placed between the disk and the door.

Fig. 4 is the bolt, shown by D' in fig. 1.

The door being closed and locked, and the bow of the key lying horizontal, as herein shown; the bar C', fig. 1, being inserted in the lock below the key, and the bolt D', fig. 1, and pin E', fig. 1, affixed, as also shown, its novelty and utility will be apparent without further specification.

I do not claim any device previously invented or patented, for fastening keys; but

What I do claim as my invention, and desire to secure by Letters Patent, is—

The key-fastener, constructed and applied substantially as herein set forth.

ROBERT S. DUNNING.
